UNITED STATES PATENT OFFICE.

ROBERT LEDING, OF WASHINGTON, DISTRICT OF COLUMBIA.

DESIGN FOR A SPOON.

SPECIFICATION forming part of Design No. 23,010, dated January 23, 1894.

Application filed April 19, 1893. Serial No. 471,041. Term of patent 3½ years.

To all whom it may concern:

Be it known that I, ROBERT LEDING, a citizen of the United States, residing at Washington, in the District of Columbia, have invented 5 certain new and useful Improvements in Designs for Spoons; and I do hereby declare the following to be a full, clear, and exact description of the invention, such as will enable others skilled in the art to which it appertains to 10 make and use the same.

In the drawing I have illustrated an obverse view of a spoon embodying my design.

In the bowl A of the spoon is shown a marine view consisting of water and sky, and a number 15 of war ships under way. At the juncture of the bowl and handle is an eagle a, mounted upon a shield b having bars and a field in which stars are shown, the shield being surrounded by a wreath, c. At the free end of 20 the handle B is an anchor d behind which appears a steering wheel e, both being located in

proximity to a capstan f. A rope n is indicated as twined round about these ship emblems and as continued for a farther distance down the handle in ornamental loops or twists. 25

The characteristic features of my design are the marine view including the war ships in the bowl; the eagle, shield, and wreath, at the junction of the bowl and handle; and the marine emblems at the free end of the handle including the rope extending along the main body portion of the handle. 30

Having thus described my design, what I claim is—

The design for the obverse of a spoon, substantially as shown and described. 35

In testimony whereof I affix my signature in presence of two witnesses.

ROBERT LEDING.
